STARTER FOR INTERNAL COMBUSTION ENGINES

Léon Gérard, Sevres, France, assignor to Paul Viet, Billancourt, Seine, France

Application February 14, 1929, Serial No. 339,957,
and in France February 16, 1928

4 Claims. (Cl. 123—179)

The present invention relates to improvements in starters for internal combustion engines, and chiefly to apparatus of this class which employ the kinetic energy of a mass rotated by suitable means and driving a shaft which may be connected with the engine.

The mass whose kinetic energy is employed may consist of a set of small electric or other motors disposed around the driving shaft, and 10 rotated about the said shaft by means of their own power, which is thus added to their kinetic energy in order to effect the starting of the engine.

In other cases, the said mass may consist of 15 heavy elements which are rotated by manual control. The apparatus according to the invention as above specified, will provide a considerable force for starting the engine, and this force may be reduced after the starter has been put in action.

Such mechanisms are susceptible of numerous applications, and in addition to their use for starting internal combustion engines such as aeroplane engines, industrial engines, Diesel and 25 semi-Diesel engines, they may be employed as servo-motors of great efficiency for all operations requiring a large initial driving power, for instance for the control of turrets for machine guns upon aeroplanes, for the turrets of battleships 30 or the like.

The following description with reference to the accompanying drawing shows an embodiment of the said invention.

Fig. 1 is a longitudinal section of a starter in 35 which the actuating mass consists of electric motors, and which comprises a pedal control and a clutch regulator.

Fig. 2 is a sectional view on line 2—2 of Fig. 1.

Fig. 3 is a partial view of the end of the shaft 40 of the rotor of one of the electric motors.

The device is primarily used in connection with the engine of an aircraft, and 1 designates the crank shaft thereof, said shaft having upon its forward end clutch teeth 2. A slidable shaft 3 is provided and is journaled in the stationary casing 12. A sleeve 6 encloses a portion of the shaft 3 and is connected thereto by splines 5.

A case 17 is confined in the casing 12 and mounted in the casing 17 are electric motors, the 50 armatures 7 thereof having their shafts 8 provided with pinions 9 and 10, which mesh, respectively, with the toothed ring 11 fixed to the casing 12 and with a similar ring 13 carried by the clutch box 14.

The box 14 contains the conventional form of

corrugated discs 15—16 serving to drive the sleeve 6, and in turn the shaft 3. The disks 15 and 16 are alternately splined to the clutch box 14 and shaft 6. The shaft 3 is provided with an annular groove 31 on which are normally engaged 60 the clutch locking members 18 operable by centrifugal force, the purpose of which will appear later.

In order to slide the shaft 3 forwardly to place the device in operation, a pivotally mounted lever 65 19 is provided and is operable to slide the shaft through the medium of the pedal 20, there being a spring 22 for urging the shaft rearwardly to its inoperative position.

The casing 12 carries a contact piece 23, for 70 supplying the ring 24 fixed to the casing with electrical energy which flows through the brushes 25 supported by the casing 12, and from thence through the brushes 26 engaged with the commutators of the armatures 7.

The fields for the armatures are indicated by the numeral 28, and 32 indicates a support for sustaining a ball bearing assembly for the shafts 8 in order to reduce friction.

The clutch locking members 18 are restrained 80 by springs 29, as customary in centrifugal governors.

The operation is as follows. Under the action of the current, the motors 7 are rotated at high speed. Due to the gearing 9—10—11—13, the 85 casing 17 containing the electric motors rotates at a speed determined by the gear ratio; the said clutching box 14 rotates at a much reduced speed which can be readily determined, since this is the case of epicycloidal gearing, thus actuating the 90 said sleeve 6 at like speed, through the clutch 15—16.

By the centrifugal force, the clutch locking members 18 (Figs. 1 and 2) will open only when the motors 7 and the casing 17 have reached a 95 speed slightly above a predetermined speed. When the said locking members 18 are opened and disengage the groove 31 it is simply necessary to slide the shaft 3 in the sleeve 6 by the lever 19 controlled by a pedal 20 (or a handle) in order to engage the clutch teeth 2 and 4.

Due to the resistance occasioned by the inertia of the engine, in the first place the clutch 14 will slip, and it will then drive the engine slowly and without shocks by means of its shaft 1, since the said clutch will progressively deliver the energy stored up by the mass in movement consisting of the combination of the electric motors and the casings 17, also the energy furnished by the said motors 7.

When the engine has been started, the driver releases his pedal 20. By the action of the spring 22 the teeth 2-4 are disengaged, and it is simply necessary to break the circuit until the electric motor is again used.

After the whole device has been rotated by the electric motors, as above stated, the circuit is not broken during the starting action, and thus the available power will consist of the kinetic 10 energy of the movable parts to which is added the force of the electric motors which constantly furnish power. The pedal (or handle) control cannot take place before the whole device has rotated at a determined speed.

15 The handle can be employed in any suitable manner to effect the control, and it may be mounted either on the outside of the aeroplane or within the aeroplane body.

I claim:

20 1. A starting mechanism for an internal combustion engine having a crankshaft to be rotated comprising a shaft slidably mounted for clutching engagement with the crank shaft of the engine and having an engine engaging member thereon. 25 a pair of motors mounted on a spider and rotatable about the shaft under their own power to drive the same, said motors being disposed in parallel relation with respect to the shaft, and a driving connection between said spider and said 30 engaging member.

2. A starting mechanism for an internal combustion engine having a crank-shaft to be rotated, comprising a sleeve, a shaft splined to the said

sleeve and slidable to engage said crank-shaft, a pair of motors rotatable about the shaft and sleeve under their own power to impart rotary movement to the sleeve, a clutch device between the sleeve and motors for driving the sleeve and thus the shaft during rotation of the motors about said shaft, a gear ring associated with the clutch device, driving connections between the motors and ring, and means for sliding the shaft for interlocking engagement with the crank shaft of 80 the engine. 85

3. A starting mechanism for internal combustion engines having a crank-shaft, comprising a slidably mounted shaft, a sleeve surrounding the shaft and splined thereto, a pair of motors rotatable about the shaft, clutch locking members normally interlocked with the shaft and operable by centrifugal force to release the shaft to permit 90 sliding thereof, a clutch device between the motors and sleeve, and a gear connection between the clutch device and motors. 95

4. A starting mechanism for an internal combustion engine having a crank-shaft to be rotated, a shaft for detachable engagement with the crank shaft when slid in one direction, means 100 for sliding said shaft, a sleeve surrounding said shaft and splined thereto, a pair of motors movable around the shaft and sleeve, a clutch device between the sleeve and motors for driving said shaft during rotation of the motors, a planetary 105 drive connection between the motors and clutch device to drive the sleeve and thus the shaft.
